(73) Assignee: **Webraiser Technologies**, Sacramento, CA (US)

(57) **CLAIM**

(**) Term: **14 Years**

The ornamental design for a mobile phone shaped internet computer terminal kiosk, as shown and described.

(21) Appl. No.: **29/127,080**

DESCRIPTION

(22) Filed: **Jul. 28, 2000**

FIG. 1 is a perspective view of the invention with an antenna portion, power button portion, numeric keypad portion and function buttons portion shown in broken lines;

(51) LOC (7) Cl. **20-02**

FIG. 2 is a front elevation view of the invention as shown in FIG. 1;

(52) U.S. Cl. **D20/10**

FIG. 3 is a top plan view of the invention;

(58) Field of Search D20/10, 41; D14/100,

FIG. 4 is a bottom plan view of the invention;

D14/102, 103, 146; 379/419, 420, 428,

FIG. 5 is a rear elevation view of the invention; and,

440, 433-436

FIG. 6 is a left side view of the invention, the right side view being a mirror image.

The broken lines in FIGS. 1 and 2 are for purposes of

illustration only and form no part of the claimed design.
